UNITED STATES PATENT OFFICE.

FRANK A. PRIMMER, OF MISHAWAKA, INDIANA.

HORSESHOE.

Application filed December 30, 1927. Serial No. 243,608.

The invention relates to new and useful improvements in horseshoes, and has for its object to provide an article of this character wherein the body of the horseshoe is made 5 of rubber or any other resilient material, and is reinforced by metallic plates, the resiliency of the tread serving to absorb and minimize the constant jar to which a horse is subjected when traveling on hard pavements which are 10 becoming quite extensive throughout the country with respect to the main highways.

A further object is to provide an article of this character constructed of light and resilient material.

15 A further object is to provide an article of this character having a body constructed from resilient material, and having toe and heel calks formed integral with the body.

20 A further object is to provide an article of this character constructed from light and resilient material and having metal calks to prevent slipping on wet or icy pavements.

25 A further object is to provide an article of this character in which means are provided to prevent stones and dirt from being picked up and becoming lodged in the bottom of the horse's hoof, or between the hoof and the horseshoe.

30 With the above and other objects in view, the invention resides in the combination and arrangement of parts as hereinafter set forth, described and claimed, it being understood that changes in the precise embodiment of the invention may be made within the scope of 35 what is claimed without departing from the spirit of the invention.

In the drawing:—

40 Fig. 1 is a perspective view of the assembled horseshoe, showing in section the method of fastening the upper plate to the body of the horseshoe;

Fig. 2 is a perspective view of the resilient body of the horseshoe;

45 Fig. 3 is a front elevation of the assembled horseshoe, showing in section the method by which the metal calks are secured to the horseshoe;

Fig. 4 is a perspective view of the bottom supporting plate; and

50 Fig. 5 is a perspective view of the plate secured across the top of the horse shoe to protect the bottom of the horse's hoof from stones and dirt.

55 Referring to the drawing, the numeral 1 designates the rubber body of the horseshoe, it being understood, however, that any other

suitable resilient material may be used in place of rubber. The body 1 of the horseshoe is constructed to have a toe calk 2, and a heel calk 3, formed integrally with the horizontal side body members 4. The toe calk 2 is of triangular shape with the pointed portion 5 extending rearwardly in the shoe and so forming a wedge which has a strong gripping action with the ground. The heel calk 65 3 extends transversely across the rear side of the shoe thus forming a support against lateral or other deformation of the rear portion of the shoe.

The body 1 is pierced by the countersunk 70 vertical holes 6 through which the rivets 7 extend to hold the upper supporting metal plate 8 to place. The metal plate 8 is shaped to conform with the outline of the horseshoe, and has formed integral with it the toe clip 75 9 at the front of the plate, and flanges 10 at the rear of the horseshoe. The flanges 10 in part serve to prevent shifting of the plate 8 with respect to the body 1 of the horseshoe, and also to prevent distortion and undue rearward flexing of the heel calk 3. Secured to 80 the bottom of the horizontal side body members 4 of the horseshoe body is a metal supporting plate 11, which is practically U-shaped.

The plate 11 is secured to the horseshoe body by means of the horseshoe nails used to secure the shoe to the hoof and which extend through the holes 12 which coincide in the plate 11, the body 1, and the plate 8. The 90 forward ends of the plate 11 have flanges 13 which are adapted to abut the opposite inner sides of the toe calk 2 of the horseshoe, and thus to give it a support against distortion and undue inward flexing; and the rearward 95 side of the plate 11 has the flange 114 which is adapted to abut the inner side of the heel calk 3 and thus support it against distortion and undue inward flexing.

The plate 11 is also secured to the body 1 100 by means of the bolts 15, whose primary purpose, however, is to furnish means for securing the metal calks 16 to the horseshoe. The bolts 15 extend through the vertical holes 17, which coincide in the plate 11, the 105 horseshoe body 1, and the plate 8, and are threaded at their upper ends and are adapted to be screwed into the threaded portion of the hole 17 in the upper plate 8. Formed integral with the bolts 15 are squared head 110 members 18, the upper sides of which have contact with the bottom plate 11 to further

secure said plate to place. The head members 18 each have a threaded bore extending upwardly through the center thereof, and which threaded bores are adapted to receive the threaded shanks of the calk members 19 which may be conical or pyramidal in shape, or in any other shape having a point. The calk members 19 are adapted to prevent slipping on wet or icy pavements, and are adjustable so that when the points are worn down they may be adjusted outwardly to provide contact with the road or pavement, under all conditions of wear of either the calks 19 or the rubber toe calks 2. Secured to the horizontal side body members 4 of the horseshoe body 1 through the vertical holes 20 therein, by nails, rivets or other suitable means, is a thin metal plate 21. The plate 21 is preferably secured between the body member 1 and the upper plate 8 so as to secure it in the most substantial manner. The purpose of the plate 21 is to provide means to prevent stones and dirt from striking or becoming lodged in the horse's hoof, or between the hoof and the horseshoe.

From the above it will be seen that a light and resilient horseshoe is provided, which is made of resilient material properly reinforced to make it sufficiently substantial for the purpose, and at the same time also to absorb shock induced in striking the road or pavement. Also that the horseshoe is provided with means to prevent slipping on wet and icy pavements, and also with means to prevent stones and dirt from becoming lodged in the horse's hoof, or between the hoof and the horseshoe.

The invention having been set forth, what is claimed as new and useful is:—

1. A horseshoe comprising a horseshoe-shaped resilient body member, a toe calk formed integral with said body member, a heel calk formed integral with said body member extending transversely thereacross, and reinforcing means secured to the upper and under sides of said horseshoe body.

2. A horseshoe comprising a resilient body member, a toe calk formed integral with said body member having a rearwardly extending tapered portion, a heel calk formed integral with said body member connecting the opposite sides of the body member, a metal reinforcing plate conforming to the shape of and secured to the upper side of said horseshoe body, and a U-shaped metal reinforcing plate secured to the under side of said horseshoe body.

3. A horseshoe comprising a resilient body member, a toe calk formed integral with said body member and extending inwardly in a tapered form, a heel calk formed integral with and disposed transversely of said body member, a reinforcing plate secured to the upper side of said horseshoe body, and a re-

inforcing plate secured to the opposite under sides of said horseshoe body.

4. A horseshoe comprising a resilient body member, a toe calk formed integral with said body member and extending rearwardly in tapered form, a heel calk formed integral with said body member and disposed transversely of said horseshoe, reinforcing plates secured to the upper and under sides of said horseshoe body, and pointed metal calks 75 carried by the horseshoe.

5. A horseshoe comprising a resilient body member, a toe calk formed integral with said body member and extending inwardly in tapered form, a heel calk formed integral with and disposed transversely of said body member, reinforcing plates secured to the upper and under sides of said body member, and pointed metal calks secured to the horseshoe by means of bolts passing through the under reinforcing plate and the resilient body member, and connected to the upper reinforcing plate.

6. A horseshoe comprising a resilient body member, a toe calk formed integral with said body member and extending inwardly in tapered form, a heel calk formed integral with and disposed transversely of said body member, reinforcing plates secured to the upper and under sides of said horseshoe body, and a thin metallic plate secured to and covering the upper open side of said horseshoe body.

7. A horseshoe comprising a resilient body member, a toe calk formed integral with said body member and extending inwardly in tapered form, a heel calk formed integral with and disposed transversely of said body member, reinforcing plates secured to the upper and under sides of said horseshoe body, pointed metal calks carried by said horseshoe, and a thin metallic plate secured to and covering the upper open side of the horseshoe body.

8. A horseshoe comprising a resilient body member having toe and heel calks formed integrally therewith, reinforcing means secured to the upper side of said body member, and reinforcing means secured to the under side of the resilient body member between the toe and heel calks thereof.

9. A horseshoe comprising a resilient body member having toe and heel calks formed integrally therewith, a reinforcing member conforming to the shape of the resilient body and secured to the upper side thereof, a reinforcing member secured to the under side of the resilient body between the toe and heel calks and conforming to the body shape between said parts.

10. A horseshoe comprising a resilient body member having toe and heel calks formed integrally therewith, a reinforcing member conforming to the shape of the resilient body secured to the upper side thereof, a reinforcing member secured to the under side 130

of the resilient body between the toe and heel calks thereof, and means carried by said last-named member adapted to support the inner sides of the toe and heel calks.

5 11. A horseshoe comprising a resilient body member having toe and heel calks formed integrally therewith, a reinforcing member conforming to the shape of the resilient body secured to the upper side thereof, 15
10 a reinforcing member secured to the under

side of the resilient body between the toe and heel calks thereof, downwardly extending flanges formed at the ends of the upper reinforcing member adapted to engage the outer end of said body member, and means carried by the under reinforcing member adapted to support the inner sides of the toe and heel calks.

In testimony whereof I affix my signature.
FRANK A. PRIMMER.
